SOCKET HOUSING

Rudolf Popp, Valparaiso, Ind., assignor to McGill Manufacturing Company, Inc., Valparaiso, Ind., a corporation of Indiana

Application June 8, 1950, Serial No. 166,895

3 Claims. (Cl. 200—168)

1

The present invention relates to a combination electric light bulb switch and socket.

More particularly, the invention relates to a detachable reinforced housing for a combination light bulb socket switch.

With combination light bulb socket and switching mechanisms of the type generally used on lamps and suspended lighting fixtures, it is desirable to provide a two-piece housing or container. By reason of the two-piece housing construction, connection of the lead-in wires to the switching mechanism can be easily accomplished, and installation of the fixture utilizing such combination, is facilitated. Combination light bulb switch and sockets having two-piece housings are well known in the art; however, they have proven unsatisfactory because of inherent defects in their design. One particularly troublesome characteristic of existing socket switches is the tendency for the two portions of the housing thereof to come apart after only a moderate amount of use. A further undesirable feature of these switches, has been the need to manufacture many different types in order to accommodate the different uses to which such switches are put. Efforts to eliminate the difficulties outlined above, have heretofore resulted in complex and expensive structures, which greatly complicated the installation of the housing.

It is therefore one object of the present invention to provide a combination light bulb switch and socket having substantially a two-piece housing that will stand up under extensive use for many years.

Another object of the invention is to provide a light bulb socket switch that can be adapted for use with many types of electrical fixtures.

A further object of the invention is the provision of a housing for a light bulb socket switch which is simple and rugged in nature, and which will facilitate installation of the socket switch.

A still further object of the invention is to provide a socket switch housing which is relatively easy and cheap to manufacture.

A feature of the invention is the provision of a two-piece housing for an electric light bulb socket switch which consists of a cap member having a notch cut in one side, and a body member telescoped within and reinforcing the walls of the cap member, and having a notch cut in one side which coacts with the notch cut in the cap member to define a reinforced, switch actuating lever accommodating aperture.

Another feature of the invention is the provision of a housing for an electric light socket

5 having an upper cap member, a lower cylindrical body member having a portion telescoped within and reinforcing the sides of the upper cap member, and an annular ring cooperating with the body member and said cap member to securely hold the housing in assembled relationship.

Still another feature of the invention is the provision of an electric light socket having a cup-shaped cap member, a cylindrical body member, 10 and an annular ring securing the body member to the cap member, the annular ring being press fitted over an annular bead on one end of the body member, and retained in place on the body member by the bead.

15 Other objects, features and many of the attendant advantages of this invention will be appreciated readily as the same becomes understood by reference to the following detailed description, when considered in connection with the 20 accompanying drawings, wherein:

Fig. 1 is a side elevational view of a light bulb switch and socket constructed in accordance with the present invention, and showing its use with one type of a standard supporting fixture;

25 Fig. 2 is a front elevational view of a disassembled light bulb switch and socket housing comprising a part of the present invention;

Fig. 3 is a sectional view of the switch housing shown in Fig. 2, after assembly;

30 Fig. 4 is a side elevational view of a modified form of the invention showing its use with a second known type of supporting fixture;

Fig. 5 is a fragmentary, side elevational view of a vertical lamp support having a combination 35 electric light socket and switch constructed in accordance with the invention, secured to one of its ends;

Fig. 6 is a sectional view of the socket switch and housing illustrated in Fig. 5, showing the 40 manner in which it is supported;

Fig. 7 is a side elevational view of a second type of lamp support upon which a combination electric light socket and switch having a housing constructed in the manner herein disclosed, can be 45 easily mounted; and

Fig. 8 is a plan view of the lamp support and lamp illustrated in Fig. 7.

Referring now to Fig. 1, the outlined container 1 represents a switching mechanism of the type disclosed in U. S. Patent No. 2,068,701, the detailed construction of which does not play a part of this invention. Switching mechanism 1 is electrically connected to a light bulb socket secured to its lower end, the outline of which is shown at 2, and a lead-in conductor 3, and is

actuated by a universally operating switching lever 4. The socket switch thus comprised, is contained within a housing having a tubular neck 5 in which a flexible, insulating nipple, not shown, is secured, and the entire assembly is suspended from lead-in conductor 3 by means of the said nipple and a set screw 6 in neck 5.

Referring next to Fig. 2, the housing containing said socket switch comprises an upper, cup-shaped cap member 8 having a turned down rim or side portion 9 externally threaded on its open end. Cap 8 has an aperture formed in the top thereof which cooperates with neck 5 to define an opening for lead-in conductors 3, and is secured to neck 5 by means of an annular flange, not shown, threadably attached to said neck. The inside diameter of cap 8 is equal to the outside diameter of an upper portion 10 of an open-ended, hollow cylindrical body member having the upper portion thereof integral with, and of greater diameter than a lower portion 11. Upper portion 10 has a rectangular, longitudinal notch 12 cut therein, and, because of its dimensions, telescopes within cap 8. Cap 8 has a rectangular, longitudinal notch 13 cut therein which coacts with notch 12, upon upper portion 10 of the body member being telescoped within cap 8, to form an aperture having reinforced walls, as is best seen in Fig. 3. Cap 8 and body 10, 11 are retained in the telescoped position by an annular ring 14 having a lower, inwardly constricting portion, and an upper, internally threaded portion 15. Ring 14 is press fitted over an annular bead 16 formed on the lower extremity of lower portion 11, and, upon being threaded onto cap 8, supports the annular lip formed between sections 10 and 11 in the manner shown in Fig. 3. The housing is constructed of brass or some other conductive material, and because of this fact it is often necessary to mount the socket switch within a paper insulator 16a, shaped to the general contour of the housing, and contained within the housing as shown in Fig. 3.

Referring now to Fig. 4 of the drawings, the outline of a combination switch mechanism 17 and light bulb socket 18, is shown, which is of the same general construction as that described in relation to Fig. 1. Switch mechanism 17 is connected to a source of electrical power through a pair of flexible conductors 19, and is controlled in its action by a universally operating switch lever 20. Switching lever 20 is connected to switching mechanism 17 through a threaded nipple 21 attached to switching mechanism 17, and that supports a pair of mounting nuts 22 and 23. Mechanism 17 and socket 18 are contained within a housing 24 almost identical in construction to the housing illustrated in Figs. 2 and 3; but which differs therefrom only in the construction of the lead-in conductor aperture lining, and the manner in which it adds support to the switch mechanism. In the modification illustrated, the socket switch and housing are fixed to a supporting mount 26 by means of nipple 24 and mounting nuts 22 and 23, and lead-in conductor 19 passes through a grommet or bushing 25 attached to the cap portion in place of an internally threaded neck. This construction allows the socket to be side mounted in a manner heretofore impossible, in that the housings of prior switches were not sufficiently rugged to allow side mounting.

Referring now to Fig. 5, a service lamp capable of extensive use, and incorporating a socket

switch constructed in accordance with the invention, is shown. The lamp comprises a vertical supporting pipe 27 having a pair of outwardly projecting arms 28 secured to the end thereof, and a lamp socket and switch 29, similar in construction to the socket switch shown in Fig. 1, secured to the ends of each of the arms. Seated in the socket portion of socket switch 29, is a light bulb 30 having half of its radiating area cut off by a half shield 31 mounted on the end of the socket switch housing, and actuated by a universally acting switching lever 4 and a pull chain 32. As is best shown in Fig. 6, the switching mechanism 1 and light bulb socket 2 are seated in a housing identical in construction to the housing illustrated in Figs. 2 and 3, and comprising upper cap portion 8 and 9 having lower cylindrical body portion 10 and 11 telescoped therewithin, and held in assembled relation by annular securing ring 14 and 15. The housing is screwed on arm 28 by means of the internally threaded, tubular neck 5 attached to upper cap portion 8 and 9, and provides a rigid support for universally acting switching lever 4, and for the half shield 31 secured to the lower end of cylindrical body portion 11. Electricity is supplied to the switching mechanism by means of conductor 3 led through arm 28 and vertical support 27 which comprise lengths of ordinary hollow pipe secured together by a T-shaped elbow.

Heretofore, the construction of a lamp in the above described manner, and from parts readily acquired in any workshop, has been impracticable in that socket switches having housings sufficiently rugged to be usable in such lamps, were not available. In known light bulb socket switches of the same general type, the cap member of the switch housing is secured to a supporting fixture, and the switch actuating lever passageway is located in the body member of the housing. In switches constructed in this manner, the downward force exerted by the switch actuating lever, is absorbed by the body member, and the upward securing force exerted by the supporting fixture, is absorbed by the cap member only; thus, the switching action tends to break the switch housing apart. In the present invention, both the cap member and the body member of the switch absorb the force of the switching action, as can best be appreciated from a study of Fig. 6. This is due to the fact that the switch actuating lever passageway is defined by the notch 13 formed in the cap member, notch 12 in the telescoped, reinforcing body member 10, and annular collar 14, and any force exerted by the switching action, is partially absorbed by all three members. This distribution of the switching force amongst all three members of the housing prevents the disassembly of the members after only a small amount of use. The telescoping construction of the housing, makes it possible to mount a half shield or other apparatus, such as a cage, on the end of the socket housing in a manner which was heretofore impossible, in that it would cause disassembly of prior switch housings. These advantages are provided without complicating the installation of the switch, for by reason of the two-piece construction of its housing, the switching mechanism can be connected to the lead-in conductors prior to closing the housing over the switching mechanism; thereby facilitating connection of the switching mechanism and the lead-in conductors. During the period that the two members of the housing

are disassembled, the press fit provided for the minimum diameter portion of annular ring 14 over bead 16, prevents the body member of the housing and the ring from coming apart; thereby precluding the loss of time and effort in searching for either of the two parts.

In addition to the above advantages, the invention lends itself for use with a great variety of supporting fixtures. One such fixture is illustrated in Fig. 7, wherein a second type of low-cost, homemade service lamp made possible by the invention, is shown. The lamp comprises a flat, two-piece, adjustable arm 34 and 35 of sheet metal having one end adapted to be pivotally secured to a wall 36, or the like, and the other end supporting a light bulb socket and switch 37 similar in construction to the socket switch shown in Fig. 4. The switch is contained within a housing 37 identical to that shown in Figs. 2 and 3, except as to the construction of the lead-in conductor accommodating passage in the upper cap portion of the housing, and the manner in which it is mounted on its supporting fixture. In the subject fixture, the socket switch 37 is mounted on the end of adjustable arm portion 35 by means of a threaded neck 21 which, as is best seen in Fig. 4, is secured to the chassis of the switching mechanism contained within housing 37. Threaded neck 21 is adapted to be selectively inserted in any one of a plurality of apertures 41 formed in the end of arm portion 35, and is secured thereto by means of a butterfly nut 42 in the manner best shown in Fig. 8. Adjustment of the light is provided by changing the length of the arm portions 34 and 35, as well as by positioning threaded neck 21 in any of the desired apertures 41. In addition, the socket switch housing can be rotated about the longitudinal axis of threaded neck 21 for the purpose of directing the light from bulb 30 in any desired direction. This provides an easily adjusted lamp which can be constructed from scrap materials usually found in a workshop, and which is made possible through the provision of a socket switch having a housing of rugged construction.

From the preceding discussion, it is readily appreciated that the invention provides a light bulb socket and switch of rugged construction, and capable of extensive use for a period of many years. Due to the double-walled strength of its housing the socket switch can be easily adapted for use in a great variety of installations, and this renders possible the attachment of auxiliary fixtures to it. Because of its simplicity of design, installation of the switch is greatly facilitated, and the loss of time in search for lost parts is prevented. And further, the housings of the switch mechanisms can be easily manufactured on a quantity basis, with only a slight modification required to adapt them for use in different types of installations.

Obviously other modifications and variations of the present invention will be suggested to those skilled in the art, in the light of the above teachings. It is therefore to be understood that changes may be made therein which are within the full intended scope of the invention as defined by the appended claims.

I claim:

1. In an electric switch socket having therein 70 switch mechanism and laterally extending operating means, a shell housing consisting of three pieces, one of said pieces being a cap portion with an extended skirt thereon and a notch extending upwardly from the edge of said skirt, and said one

piece having a thread at the edge of said skirt, a second piece being a bottom portion having an extended skirt thereon and a notch extending downwardly from the edge thereof, with the skirt of each portion corresponding substantially in length and with said skirt of said one piece telescopically receiving the second-piece skirt therein to substantially the full length of the skirts and with the notches in each corresponding in position to one another for the laterally extending operating means to be positioned therein, and the third piece of said socket comprising an assembly ring having a threaded portion at one edge and a flange at the other carried on said second piece 15 to threadably engage the thread on the first piece and upon tightening to pull the first and second pieces into assembled position with the skirt portions telescoped.

2. In an electric switch socket having therein 20 switch mechanism and laterally extending operating means, a shell housing consisting of three pieces, one of said pieces being a cap portion having an extended skirt thereon and a thread at the edge of said skirt, a second piece being a bottom portion having an extended skirt thereon, with the skirt of each portion corresponding substantially in length and with said skirt of said one piece telescopically receiving the second-piece skirt therein to substantially the full length of the skirts, and with each said skirt portion having a notch therein with the notches corresponding in position to one another and having the laterally extending operating means positioned therein, and the third piece of said socket comprising 25 an assembly ring carried on said second piece having a threaded portion at one edge threadably engaging the thread on said one piece to pull said one piece and second piece into an assembled position, and said third piece having a flange 30 thereon of such a dimension as to prevent the removal thereof from said second piece.

3. In an electric socket having therein switch 35 mechanism and operating means extending laterally therefrom, a shell housing consisting of only three members, a cup-shaped cap member having a thread section at the edge thereof, a body member having a ridge thereon intermediate a portion thereof of one diameter and another portion thereof of a lesser diameter, with said members each having an aperture therein correspondingly positioned in the assembled socket and having the operating means therein which prevents lateral turning movement between said two members, and with the third member comprising a relatively narrow annular ring rotatable relative 40 to the two members with a thread section and a constricted section, said ring being retained on said body member at said portion of lesser diameter by the constricted portion of the ring, and being threadably connectible with said thread section of the cap member and engageable at the ridge of said body member to pull the cap member and body member into an assembled relation and maintain the same.

RUDOLF POPP.
